UNITED STATES PATENT OFFICE.

JOHN WICKS, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed April 1, 1921, Serial No. 457,743. Renewed October 9, 1925.

The present invention relates in general to telephone systems, but is concerned more particularly with methods of establishing toll or long distance connections automatically. The object of the invention may be said to consist broadly in the production of a new and improved toll trunking system in which long distance connections are established automatically, together with the addition of improved circuits and apparatus whereby such systems may be put into effective operation.

The above indicates in broad terms the scope of the invention. Various features included in the working of the complete system will not now be specifically mentioned, but will be described in the specification which is to follow, and pointed out in the claims.

Of the accompanying drawings to which reference will be made in the specification, Figs. 1, 2, 3, 4, and 5, when arranged in order with corresponding lines at the ends thereof in alignment, represent diagrammatically sufficient of the apparatus used in making a long distance connection in a system embodying the principles of the present invention to enable it to be understood. Fig. 6 is a schematic diagram illustrating the general layout of the system; while Fig. 7 shows a cord circuit which is a modification of the one shown in Fig. 2.

Referring to Fig. 6, a manual exchange and two automatic exchanges are shown, which, beginning at the left, will be designated, respectively, as the No. 1 exchange, the No. 2 exchange, and the No. 3 exchange. These exchanges are assumed to be located in different cities and although the exact size is of no great consequence they may each have a capacity of 10,000 lines. On the assumption that the capacity is as noted above, local connections in the No. 2 and No. 3 exchanges will be established through the medium of individual line switches or trunk selectors, first selectors, second selectors, and connectors. For example, in the No. 2 exchange the subscriber at substation A¹ is able to establish connection with the subscriber at substation A² through the medium of the individual line switch C, first selector E, second selector F, and the connector H. This is the usual percentage trunking system and is mentioned because of the fact that the greater portion thereof,

comprising the second selectors and the connector switches, also forms a part of a second trunking system used only for the establishment of toll connections. The same is true for the No. 3 exchange. The No. 1 exchange is a manual exchange and connections are established between the various subscribers, by operators, in the well known manner.

Each exchange is provided with a toll board presided over by one or more operators who establish all outgoing toll connections. The operators in any particular automatic exchange have access to the local subscribers' lines by way of a first selector and thence by way of the regular trunking system. Referring again to Fig. 6 the jack J⁶ is one terminal of a trunk which extends to the first selector E'. The selector E' in common with the other first selectors such as the selector E, has access to the regular second selectors. It is seen therefore that the local trunking system is used in completing both toll and local calls. The No. 3 exchange is arranged in substantially the same manner as the No. 2 exchange. It is assumed for convenience that the toll operators in exchange No. 1 have access to jacks in which the local subscribers' lines are multiplied. Accordingly to complete a connection to a local subscriber the toll operator need only insert the plug of a cord circuit in the proper jack.

Proceeding now to the trunking between exchanges, the No. 1 exchange and the No. 2 exchange may be interconnected by a group of toll lines sufficient in number to handle the traffic. One of these toll lines is the toll line X. Similarly, a group of toll lines one of which is the toll line Z connects the No. 2 exchange and the No. 3 exchange. There are no toll lines directly extending between the No. 1 and the No. 3 exchanges and, therefore, connections between these two points must necessarily be extended by way of the No. 2 exchange. This situation may arise in either of two ways. Either or both of the No. 1 and No. 3 exchanges may be of relatively small size and so located as to be subsidiary to exchange No. 2. In such a case it would be uneconomical to provide a third group of toll lines extending directly between the No. 1 and the No. 3 exchange. The second case arises when the

exchanges, which may all be of one size, are located in approximately a straight line or where for topographical reasons the toll lines from exchange No. 1 to exchange No. 5 3 pass through or near the city in which exchange No. 2 is located. Under these circumstances it has been found most efficient to cut the through toll lines at the intermediate exchange, thereby making each section 10 available for short haul messages, and complete all through calls by means of switching apparatus at the No. 2 or intermediate exchange.

It will be appreciated now that the toll 15 lines and switching apparatus comprise a second trunking system and it will be shown in the following that this second system is merged into the regular trunking system at each of the automatic exchanges.

20 The toll lines terminate at each end in the usual manual drops and jacks. That is, the toll line X extends from jack J² in the No. 1 exchange to jack J⁴ in the No. 2 exchange by way of the repeater D, and the toll line Z extends from jack J⁸ in the No. 25 exchange to the jack J¹⁰ in the No. 3 exchange by way of repeaters D' and D². The repeaters D, D' and D² are associated with the first selectors E', E², and E⁴, respectively. Considering now the No. 2 or 30 intermediate exchange the banks of all the toll first selectors including selectors E' and E² are connected in multiple and the first 9 levels, assuming that the usual 35 Strowger type of switches are used are multiplied with the first 9 levels of the regular first selectors as is clearly shown in Fig. 6. Since the toll operators are never required to call the toll recording operator, who is 40 reached by calling O, there is thus left available for other purposes the tenth level of the toll first selectors. This level is used for through switching and for this purpose a group of toll second selectors is provided, 45 one of which is indicated by reference character F'. These toll selectors are accessible in common to all the toll first selectors in the No. 2 exchange and have common access to all the groups of trunk lines terminating 50 in the No. 2 exchange, it being understood of course that there may be a number of such groups extending each to a different city, in addition to the two groups indicated in Fig. 6. No toll second selectors are 55 shown in the No. 3 exchange. In case there should be a fourth exchange the No. 3 exchange would take on the character of an intermediate exchange and would be equipped in the same manner as exchange 60 No. 2. It is now seen that the same toll first selectors are used for both local toll connections and for through calls from the No. 1 to the No. 3 exchange or to any other exchange that may be included in the system.

To further illustrate the general trunking system a call may be traced from the substation A in the No. 1 exchange to the substation A² in the No. 2 exchange. The connection is of course completed by the 70 operator in the No. 1 exchange and is extended to the called line over the following path: jack J², toll line X, repeater D, toll selector E', second selector F, connector H. The connection, to the local subscriber at 75 substation A, is set up by way of the cord circuit O and the jack J'. The operator is provided with a jack J³ subsidiary to jack J² for the purpose of controlling the automatic switches. The dial cord P is inserted 80 into the dial jack J³ and the calling device associated therewith is turned in the usual manner to make the connection. Assuming now that the called substation is the substation A³ in the No. 3 exchange the connection thereto may be extended over the following path: jack J², toll line X, repeater D, toll first selector E', toll second selector F', repeater D', toll line Z, repeater D², toll first selector E⁴, second selector F², 90 and connector H'.

It is thought that the foregoing is sufficient to make clear the general layout of the system. Reference will now be had to the circuit drawings comprising Figs. 1-5, 95 inclusive, for a description of the apparatus involved. These drawings show diagrammatically all the equipment necessary to establish a complete long distance connection between the substation A and a trunk 100 line leading to a first selector in the exchange No. 3, it being understood that the connection is completed through the medium of the local trunking system to any subscriber in the No. 3 exchange.

The apparatus shown in Fig. 1 is located in the No. 1 exchange; the apparatus shown in Figs. 2, 3, and 4, is located in the No. 2 exchange; while the apparatus shown in Fig. 5 is located in the No. 3 exchange.

The substation A is an ordinary manual substation having the usual talking and signalling instrumentalities and terminates in the manual exchange in an answering jack J which is located at an "A" operator's position. The substations A', A², A³, and A⁴ which are indicated in Fig. 6 but not shown in detail in the drawings are of the usual automatic type.

The individual line switches indicated 120 schematically in Fig. 6 may be of any approved type of trunk selector. Line switches are well known and therefore will not be described herein. It will be sufficient to say that through the medium of line switch C 125 the line of substation A' is given access to a plurality of first selector switches, such as the selector E, which form part of the local trunking system previously described.

The selector switches E, E', E², E³, E⁴, F, 130

F' , and F^2 are mechanically of the usual Strowger vertical and rotary type of switches having the bank contacts arranged in horizontal rows or levels. The circuits of these 6 selectors are all the same and are shown in detail in Fig. 3.

The connector switches such as H and H' , shown schematically in Fig. 6, are mechanically the same as the selectors. The circuit 10 used in the connectors is a simple two wire circuit and is in common use.

Attention is particularly called to the repeaters among which are the repeaters D , D' and D^2 . The circuit of each of these repeaters is so arranged that the regular selector circuit for use in the local trunking system need not be changed when the same selector is to be used for toll connections. The circuits of any two of these repeaters are identical 20 and are shown complete and will be described fully hereinafter.

The toll lines such as the toll lines X and Z have the usual repeating coils such as the repeating coils T , T' , T^2 , and T^3 at each end 25 thereof. The dialing circuit, or we might say the switch control circuit, used in connection with these toll lines is the well known simplex circuit. The operation of this circuit will be pointed out and fully explained 30 hereinafter.

The toll operator's cord circuits, such as the cord circuit O , Fig. 1, in the No. 1 exchange are arranged with a ringing key on either end. The right hand or outgoing end 35 is not altered but is the same as would be used were the No. 2 exchange manually operated. The left hand or local end is identical with the calling end of the ordinary manual operator's cord circuit. The left hand or outgoing end of the cord circuit O' , Fig. 2, in the No. 2 exchange is the same as the right hand or outgoing end of the cord circuit O in the No. 1 exchange, the right hand end of the cord circuit O' having the 40 proper circuit arrangements to enable the operator to control the local switches, and to get answering supervision. Additional cord circuits such as the one shown in Fig. 7 may also be provided at the No. 2 exchange for 45 use in establishing direct manual connections between toll lines. The cord circuits used in the No. 3 exchange are understood to be identical with those used in the No. 2 exchange.

50 The apparatus having been described in general will now be described in connection with a detailed description of its operation. For this purpose it will be assumed that the subscriber at substation A, Fig. 1, desires to obtain connection with a subscriber in the No. 3 exchange.

In order to initiate a long distance call the subscriber at substation A must get into communication with a so called toll recording operator in the No. 1 exchange. Any ap-

proved method of accomplishing this object will serve, but since the substation A is a manual substation it will be assumed that the subscriber calls the toll recording operator manually and in the well known manner 50 which need not be explained. When the toll recording operator answers the calling subscriber gives her the desired information. The toll recording operator records the information on a ticket or in some other way, 75 and then tells the calling subscriber to hang up his receiver. The order is then placed in the hands of the toll operator whose duty it is to complete the connection.

In the case under consideration the wanted subscriber's line terminates in the No. 3 exchange which must be reached by way of the No. 2 exchange. The toll operator, therefore, after first ascertaining that the toll line X extending to the No. 2 exchange 80 is idle, as indicated by the unoperated condition of the visual signal 34, inserts the outgoing plug of an idle cord circuit, the cord circuit O , for example, into the jack J^2 . Thereupon the following circuit is completed: from ground by way of cut off relay 35, the sleeve of jack J^2 , corresponding contact on the plug of the cord circuit O , and relay 10 to battery. The two relays energize in series but the energization of relay 10 has no 95 effect at this time. Cut off relay 35 upon energizing, removes at armature 36 the bridge of the upper winding of relay 39 from the conductors 23 and 24, and at armature 37 closes a circuit for the visual 100 signal 34. The visual signal 34, as well as its multiples in front of the other toll operators in the No. 1 exchange, is accordingly operated. A branch of this circuit also extends by way of the resting contact of spring 105 25 of jack J^3 and said spring to battery through the repeating relay 27. Repeating relay 27 upon energizing, places battery out on the toll line X by way of resistance R' , working contact of armature 28 and said 110 armature, conductor 53, and the upper and lower right windings of repeating coil T . The result is, that line relay 116 of the repeater D , on the other end of the trunk line, in the No. 2 exchange immediately energizes 115 by way of the following circuit: from ground through line relay 116, resting contact of armature 129 and said armature, resting contact of armature 119 and said armature, conductor 54, upper and lower left windings 120 of the repeating coil T' , trunk line X , and thence by way of previously traced circuit to battery. Line relay 116, upon energizing, closes at armature 136 a circuit for the slow acting release relay 117. Upon energizing, 125 release relay 117 grounds the release trunk conductor 164 of the selector E' , associated with the repeater D , for a purpose to be hereinafter explained. When ground is placed on release trunk conductor 164, relay 130

115 energizes and at armature 135 places ground on release trunk conductor 161 of repeater D to make the said repeater busy to the selectors having access to it. At armatures 134 and 142, the circuit extending to dial jack J^5 is opened so as to prevent any accidental insertion of the plug of dial cord P', Fig. 4, into the said jack from interfering with the connection. As a further result of the energization of the line relay 116 the following bridge is closed across trunk conductors 163 and 165 of selector E'. From trunk conductor 163 by way of the normally closed contacts controlled by armature 125, resistance R⁵, working contact of armature 137 of line relay 116 and said armature, and trunk conductor 165. When this bridge is closed across the trunk conductors 163 and 165 the line relay 175 of the selector E', Fig. 3, is energized and at armature 183 operates the release relay 176, thereby preparing the selector for its usual operations.

The toll operator now inserts the plug of the dial cord P into the dial jack J^3 thereby operating the spring 25 of the said jack. The circuit of repeating relay 27 is now shifted so as to include the spring 26 of jack J^3 and the calling device S of the cord P.

The toll operator in the No. 1 exchange may now operate her calling device in accordance with the first digit of the desired number. Upon referring to Fig. 6 and remembering that the connection is to be extended to the No. 3 exchange, it becomes evident that the first digit called must necessarily be 0. When the calling device S is operated in accordance with the first digit 0 of the desired number the circuit of repeating relay 27 associated with the dial jack J^3 is broken ten times momentarily. Each time the circuit of the repeating relay 27 is broken it, upon deenergizing, interrupts the circuit of the line relay 116 of the repeater D in the No. 2 exchange. The line relay 116 of the repeater D repeats these interruptions at armature 137 to the trunk line comprising conductors 163 and 165 and extending to the selector E', and also operates slow relay 118 over the following circuit: from ground by way of armature 136 and its resting contact, armature 138 and its working contact, and slow acting relay 118 to battery. Relay 118 upon energizing closes at armature 141 a bridge across trunk conductors 163 and 165 by a more direct path, excluding resistance R⁵, so as to obtain a better switch control circuit, and at armature 140 closes a circuit for relay 112 by way of the resting contact of armature 130 and said armature. Upon energizing, relay 112 locks itself to release trunk conductor 164 at armature 127: shifts, at armatures 125 and 128, the original bridge closed across conductors 163 and 165 so as to include the work-

ing contact of armature 125 and said armature, upper right winding of repeating coil T', resistance R², resting contact of armature 121 and said armature, lower right winding of repeating coil T', and armature 128 and its working contact, instead of resistance R⁵, and at armature 126 closes the following circuit for the cut off relay 102 associated with jack J^4 : from ground by way of cut off relay 102, armature 133 and its resting contact, armature 126 and its working contact, and resistance R³ to battery. Upon energizing, cut off relay 102 opens at armature 103 the circuit of the upper winding of relay 100, and closes at armature 104 an energizing circuit for visual signal 106 and its multiples to apprise the operators in the No. 2 exchange of the fact that the toll line X is busy.

In response to the interruptions produced in the bridge across conductors 163 and 165 at armature 137 of line relay 116 of repeater D, the line relay 175 of the selector E' is deenergized ten times momentarily and at each deenergization operates the vertical magnet 180 in series with the slow acting relay 177 over the following circuit: from ground by way of the resting contact of armature 192 and said armature, armature 183 and its resting contact, armature 185 and its working contact, slow acting series relay 177, and vertical magnet 180 to battery. By the operation of the vertical magnet the switch shaft and wipers are raised step by step until the wipers stand opposite the tenth level of bank contacts. Relay 177 energizes and retains its armature attracted throughout the vertical movement of the shaft, and upon the closure of the vertical off normal springs 186, completes a circuit for the stepping relay 178. Upon energizing, relay 178 prepares the circuit of the rotary magnet 181 at armature 189, and at armature 188 establishes a locking circuit for itself in series with the resting contact of the armature of rotary magnet 181 and said armature. At the end of the vertical movement of the shaft the slow acting relay 177 deenergizes and completes the circuit for the rotary magnet 181 which thereupon energizes to advance the wipers 194-196, inclusive, into engagement with the first set of bank contacts in the level opposite which they are raised. The rotary magnet also attracts its armature and thereby breaks the circuit of the stepping relay 178, whereupon the said relay deenergizes and breaks the circuit of the rotary magnet, at armature 189, which thereupon deenergizes also and again closes the circuit of the stepping relay.

The operation now depends upon whether the test contact with which the test wiper 195 is in engagement is busy or idle. If the test contact is busy there is a ground poten-

tial on it and the stepping relay energizes again and the same cycle of operation is repeated over and over until an idle or ungrounded test contact is reached. When an idle set of contacts is reached the switching relay 179 energizes in series with the stepping relay 178 over the following circuit: from ground by way of release trunk conductor 164, switching relay 179, resting contact of the armature of the rotary magnet 181 and said armature, off normal contacts 186, and stepping relay 178 to battery. Relay 178, however, due to its relatively small number of turns and comparatively stiff adjustment, does not energize over this circuit. In the present case, however, it is assumed that the test contact 198 is the first one found idle. That being the case, the energization of switching relay 179 switches the connection through to the trunk line terminating in bank contacts 197-199, inclusive, and leading to the toll second selector F'.

When the connection is thus extended the line and release relays 218 and 219 in the selector F' immediately energize and prepare the switch for operation in the usual manner. The toll operator in the No. 1 exchange may now operate her calling device in accordance with the second digit of the desired number. Referring again to the layout shown in Fig. 6, it becomes evident that the second digit must be 2 since it is the second level of the selector F' that gives access to the trunk line Z leading to the No. 2 exchange. When the operator operates her calling device in accordance with the digit 2 the selector F' raises its wipers 222, 223 and 224 step by step until they stand opposite the second level of bank contacts and then rotates them in search of an idle trunk line.

The operation of the selector F' is exactly the same as the operation of the selector E' and consequently need not be explained in detail. Assuming that the trunk line terminating in bank contacts 225-227, inclusive, is the first one found idle, the energization of the switching relay 234 switches the connection through by way of the trunk line comprising conductors 231-233, inclusive, to the repeater E'.

Referring back to the operation of the repeater D it will be remembered that when the release relay 117 energized it placed ground upon the release trunk conductor 164 of the selector E'. This ground is now extended forward by way of release trunk conductor 232, armature 262 and its resting contact, armature 263 and its resting contact, and relay 238 to battery. Relay 238, upon energizing, closes at armature 243 a circuit for relay 244. Relay 244 upon energizing, closes at armature 245 the following circuit for the cut off relay 248 asso-

ciated with the jack J⁸: from ground by way of cut off relay 248, armature 245 and its working contact, and resistance R⁷ to battery. Cut off relay 248, upon energizing, removes the upper winding of relay 249 from in bridge of the conductors leading to jack J⁸, and at armature 251 operates the visual 247 and its multiples in front of the other operators. Returning now to the relay 238 a further result of its energization is that it closes a bridge across trunk conductors 231 and 233 including the upper and lower windings of the line relay 258, armatures 240 and 241 and their working contacts, and the upper and lower left windings of the repeating coil T². The result of the closure of this bridge is that line relay 258 energizes and at armature 259 places battery out on trunk line Z by way of the following circuit: from battery through resistance R⁶, armature 259 and its working contact, working contact of armature 239 and said armature, conductor 260, and the upper and lower right windings of repeating coil T². When battery is thus placed on the trunk line Z the line relay 303 of the repeater D' in the No. 3 exchange is energized over the following circuit: from ground by way of line relay 303, resting contact of armature 302 and said armature, resting contact of armature 301 and said armature, conductor 300, upper and lower left windings of repeating coil T², trunk line Z, and thence by way of the previously traced circuit to battery. It will be appreciated that, since the circuit of repeater D' is exactly the same as the circuit of repeater D and that the repeater D' is also connected to its associated jack in the same manner as the repeater D is connected to its associated jack, the results in this case are precisely the same as when the toll operator in the No. 1 exchange inserts the calling plug of a cord circuit in the jack J² of the trunk line X. Accordingly the repeater D' closes a bridge across the line conductors 304 and 305, and places ground on release trunk conductors 306 and 326.

Upon referring to the schematic diagram shown in Fig. 6 it is noted that the repeater D' is directly connected to a toll first selector designated by the reference character E⁴. Since this selector is exactly the same as the selectors E' and F' already shown and described it is not necessary to show and describe the circuit of the selector E⁴. It will suffice to say that when the operator again turns her calling device that the circuit of the upper winding of the ringing response relay associated with jack J¹⁰ is opened; the busy visual associated with the said jack is operated, the talking circuit is closed through to the selector ahead, and the selector E⁴ operates to raise its wipers to the desired level and rotate them to pick

out an idle trunk line leading to a second selector such as F², Fig. 6.

When the calling device is turned again the second selector that has been selected 5 operates to give access to a connector switch such as the connector H' also shown in Fig. 6. In response to the last two digits of the called number the connector extends the connection to the desired line and rings the bell at the called substation. The operator, having finished dialling removes the plug 10 of the dial cord P from the dial jack J³ after which the repeating relay 27 is maintained energized over its original energizing 15 circuit.

When the called subscriber hears his bell ringing he removes his receiver. He may now converse with the toll operator in the No. 1 exchange, his transmitter being supplied 20 with talking current from the connector that is used to obtain access with his line. After ascertaining that the desired subscriber has answered, the toll operator tells him to wait while she calls the subscriber 25 that first initiated the call. There might be any one of several methods used in recalling this subscriber but as before stated it is assumed in the present case that the toll operator has in front of her a multiple 30 of all the lines terminating in exchange No. 1. That being the case all that is necessary for her to do is to insert the other plug belonging to the cord circuit O into the jack J' of the substation A and 35 operate the ringing key K. When the subscriber at substation A answers in response to the ringing of his bell the toll operator tells him that the called subscriber is on the line. The calling and called subscribers 40 may now converse with each other, the talking circuit being outlined by heavy conductors as far as the repeater D². From thence the circuit is old and well understood and of course need not be shown.

45 When the conversation is finished both subscribers hang up their receivers. When the subscriber at substation A replaces his receiver he opens the circuit of the supervisory relay associated with supervisory 50 lamp L and thereby lights the said lamp in series with the cut off relay 15 of jack J. The toll operator upon noting the lighted condition of the supervisory lamp L knows that the conversation is finished and hence 55 pulls down the connection.

When the plug is removed from jack J' the circuit of the lamp L is broken and likewise the circuit of the cut off relay 15. Cut off relay 15, upon deenergizing makes the 60 line of substation A ready for another call.

When the plug is removed from the jack J² the circuit of the cut off relay 35 is broken. Cut off relay 35, upon deenergizing, opens at armature 37 the circuit of visual 65 signal 34 and its multiples and also of re-

peating relay 27. Repeating relay 27 upon deenergizing, opens at armature 28 the circuit of line relay 116 of repeater D in the No. 2 exchange. Upon deenergizing, the line relay 116 opens at armature 137 the circuit of line relay 258 of repeater D', and at 70 armature 136 closes the circuit of slow acting relay 118 and opens the circuit of release relay 117. Upon deenergizing, release relay 117 opens at armature 138 the circuit 75 of slow acting relay 118, and removes ground from release trunk conductor 164 thereby allowing relays 115 and 112 to deenergize. Relay 115, upon deenergizing, removes the busy potential from release trunk conductor 161. Relay 112 upon deenergizing opens at armature 126 the circuit of cut off relay 102. Relay 102 accordingly deenergizes and opens at armature 104 the circuit 80 of visual signal 106 and its multiples, 85 and the said signals accordingly deenergize. When ground is removed from release trunk conductor 164 relay 238 of repeater D' deenergizes and the selectors E' and F' release in the usual manner. The deenergization of 90 relay 238 results in the deenergization of all the relays associated with repeater D' and jack J⁸ that have been energized during the connection. Line relay 258 the circuit of 95 which was opened by the deenergization of line relay 116 of repeater D, upon deenergizing, opens at armature 259 the circuit of line relay 303 of repeater D². Line relay 303 upon deenergizing, opens the bridge across conductors 304 and 305. When this 100 is done the circuit of the line relay of the connector to which the connection has been extended is broken and the connector is released in the usual manner. The release relay 307 of the repeater D² falls back about 105 the same time as the release relay of the connector and the two of them remove ground from release trunk conductor 306 thereby releasing the intervening selectors. The connection is now completely released 110 and all the apparatus used is restored to common use.

We shall now assume that the subscriber at substation A desires to call the subscriber at substation A', Fig. 6, in exchange No. 2, 115 whose number is 9110, the method of procedure in this case in calling the toll recording operator being as hereinbefore described. We shall assume further that when the toll operator in exchange No. 1 starts to 120 establish the connection to the subscriber at substation A' she finds that the trunk line X is idle and accordingly inserts the plug of an idle cord circuit, the cord circuit O, for example, into the associated jack J². 125 Obviously when this is done the same circuit operations take place as took place in the previous call when the said operator inserted the same plug into the same jack. In this case as before the visual signal 34 and 130

its multiples in front of the other operators are energized, and repeating relay 27 is energized and closes the circuit of the line relay 116 of repeater D. The final result is 5 that the selector E' is made ready for operation in the usual manner and ground is placed upon release trunk conductor 161 of repeater D. The operator now inserts the 10 plug of the dial cord P into the jack J⁹ thereby including the calling device S in the circuit of repeating relay 27.

The operator may now operate her calling device in accordance with the first digit 9 of the desired number. Thereupon, the selector 15 E' raises its shaft and wipers step by step until the latter stand opposite the ninth level of bank contacts and rotates them to pick out an idle trunk line. We shall assume that the trunk line terminating in the contacts 200, 201 and 202 is the first one found idle and consequently the one selected. The conductors extending from these bank contacts are understood to extend to and terminate in a 20 second selector switch such as the selector 25 F, Fig. 6. The line and release relays of the said selector accordingly energize preparing the switch for operation in the usual manner.

In the repeater D, as a result of calling 30 the first digit the armatures 125 and 128 of relay 112 are operated to close thereat two points in the talking circuit as outlined by the heavy conductors, and the cut off relay associated with the jack J⁴ is operated with 35 the result that the upper winding of relay 100 is removed from in bridge of the conductors leading to jack J⁴ and the visual signal 106 together with its multiples in front of the other operators is energized to 40 inform the operators in exchange No. 2 that the trunk line X is in use.

The operator in exchange No. 1 may now manipulate her calling device S in accordance with the remaining digits of the desired 45 number whereupon the second selector to which the connection has been extended and a connector switch such as the connector H, Fig. 6 are operated to give access to the called line. The remainder of the operation being old, need not be explained.

We shall assume that some subscriber in exchange No. 2 desires to call the subscriber at substation A in exchange No. 1. In order to initiate such a call the subscriber in exchange No. 2 removes his receiver and dials the digit 0 thereby causing a first selector such as the selector E, Fig. 6, to raise its wipers to the tenth level and rotate them to pick out an idle trunk line leading 55 to the toll recording operator. Since the calling of the toll recording operator has nothing in particular to do with the present invention it will not be necessary to describe this in detail. It will suffice to say that 60 when the toll recording operator answers

the subscriber gives the desired information and assuming that the operator makes out a ticket she passes it over to the toll operator.

The toll operator, in order to call the subscriber at substation A, inserts the plug of an idle cord circuit, the cord circuit O' for example, into the jack associated with an idle trunk line such as the jack J⁴ associated with the trunk line X. Assuming that it is the 70 jack J⁴, the cut off relay 102 is operated in series with sleeve relay 107. Upon energizing, cut off relay 102 opens the circuit of the upper winding of relay 100 at armature 103, and at armature 104 and its working contact 80 operates the visual signal 106 and its multiples in front of the other operators. A branch of the energizing circuit for visual signal 106 extends by way of armature 123 and its resting contact, and resting contact 85 of armature 166 and said armature to battery through relay 113. Relay 113, upon energizing, places ground on release trunk conductor 161 at armature 131, thereby making the repeater D busy to the selectors which 90 have access to it. As a further result of the energization of relay 113, it places battery out on the trunk line X by way of resistance R⁴, resting contact of armature 132 and said armature, working contact of armature 129 95 and said armature, resting contact of armature 119 and said armature, conductor 54, and the upper and lower left windings of repeating coil T'. This latter operation, however, has no particular utility in this case, 100 since the exchange No. 1 is a manual exchange, but is done in order that repeaters such as repeaters D and D' may be interchangeable, and also that repeaters in exchange No. 2 will not need to be changed in 105 case the No. 1 exchange is later cut over to automatic operation. The dial jack J⁵ is associated with the repeater for the same reason.

The operator now operates key K² in such 110 a direction as to project generator out on the trunk line X thereby operating relay 39 associated with jack J². Relay 39, upon energizing, closes a locking circuit for itself and an energizing circuit for lamp L² and the visual signal 34 and its multiples in front of the other operators. A branch of this circuit also extends by way of resting contact of spring 25 of jack J³ and said contact, to repeating relay 27. Repeating relay 27 upon 115 energizing, places battery through resistance R' upon the trunk line. This, however, does not have any utility at the present time.

The toll operator in exchange No. 1 upon 120 seeing the lighted condition of lamp L² inserts the plug of an idle cord circuit, the cord circuit O for example, into the jack J² whereupon the cut off relay 35 is energized in series with relay 10 in the usual manner. Upon energizing, cut off relay 35 unlocks 125 130

the relay 39 at armature 37 thus extinguishing the line lamp L^2 and at armature 37 closes another circuit for the visual signal 34 and its multiples. The toll operator in exchange No. 1 now learns from the toll operator in exchange No. 2 the number of the called subscriber, and thereupon completes the connection by way of the other plug of the cord circuit in use and signals the called subscriber.

When the called subscriber answers he can converse with the toll operator in exchange No. 2. She tells him to wait on the line while she calls the subscriber that desires connection with him. The operator then inserts the other plug of cord circuit O' into the jack J^6 , the said jack being associated, on the toll board, with the jacks J^4 and J^5 but is shown at some distance away so as to be able to show the cord circuit fully. The same is true for the other jacks similarly located. When the plug is inserted into the jack J^6 ground through the low wound sleeve relay 110' and the sleeve of the cord is supplied to release trunk conductor 164. Relay 115 immediately energizes and at armature 135 shifts the circuit of release trunk conductor 161 so as to include the working contact of armature 135 instead of its resting contact, and armature 131 and its working contact. The low wound relay 110' upon energizing opens at armature 111' a point in the circuit of lamp L^5 . The polarized relay 159 in the cord circuit O' is included in a bridge across conductors 161 and 165 the said bridge including the heavy talking conductors and the right hand winding of the repeating coil. The two relays, supervisory relay 159 of cord circuit O' and line relay 175 of the repeater E, energize in series, the current flow in relay 159 at this time being in such a direction as to operate the said relay. Upon energizing, polarized relay 159 closes a point in the circuit of the supervisory lamp L^5 . The line relay 175 of selector E', upon energizing, closes the circuit for release relay 176, which upon energizing, prepares the switch for operation in the usual manner and at armature 184 places ground on release trunk conductor 164 thereby shunting relay 110' in the cord circuit O' . Relay 110' accordingly deenergizes and lights the supervisory lamp L^5 . The operator now throws her key K^3 ; thereby removing the polarized relay 159 and the associated windings of the repeating coil from the bridge across conductors 163 and 165 and substituting the calling device S^2 therefor. Relay 159 accordingly deenergizes and extinguishes the lamp L^5 .

The operator may now operate her calling device S^2 in accordance with the digits of the desired number whereupon a first and second selector and a connector, such as the connector H, Fig. 6, are operated in the

usual manner to give access to the calling line.

After the operator has finished dialling the number she restores the key K^3 to normal thereby reinserting the polarized relay 159 into the before mentioned bridge across conductors 163 and 165, whereupon, the said relay operates its armature to relight the supervisory lamp L^5 . When the calling subscriber answers, the connector switch operates to reverse the current flow in conductors 163 and 165. As a result the polarized relay 159 included in bridge thereof retracts its armature thereby extinguishing the lamp L^5 to give the operator answering supervision. The operator upon noting that the lamp L^5 has become extinguished knows that the calling subscriber has answered and accordingly throws her listening key and tells him that the party whom he desires is on the line.

The subscribers may now converse with each other in the usual manner and when the conversation is finished they replace their receivers. When the receiver is replaced at 90 substation A the supervisory lamp L is lighted in the usual manner. When the receiver is replaced at the substation of the subscriber in exchange No. 2, the connector switch reverses the current flow in conductors 163 and 165 back to normal, thereby reoperating the polarized relay 159 and relighting the supervisory lamp L^5 . The operator in exchange No. 2 upon perceiving the disconnect signal removes the plug from jack J^6 , thereby releasing the automatic switches in the usual manner, and operates her ringing key to project ringing current out over the toll line X and then removes the plug from jack J^4 . In response to the 105 ringing current sent out over the said toll line, relay 29 in the cord circuit O is energized and at armature 30 closes a locking circuit for itself and an energizing circuit for supervisory lamp L' by way of the resting contact of spring 33 and the said spring and the armature and contact of relay 10. The operator in exchange No. 1, upon seeing the lighted condition of the lamps L and L' , pulls down the connection. The apparatus is now all restored to normal.

We shall now assume that the toll operator in exchange No. 2 receives a ticket calling for a connection between some subscriber in the said exchange and a subscriber in the 120 No. 3 exchange. Upon the receipt of the said ticket the operator inserts the plug of an idle cord circuit, the left hand or outgoing plug of the cord circuit O' for example, into the jack associated with an idle 125 trunk line, such as jack J^8 associated with the trunk line Z, leading to the No. 3 exchange. When the plug is inserted into the said jack the cut off relay 248 is energized 130 in the usual manner and closes at armature

251 a circuit for the visual signal 247. A branch of the energizing circuit for the visual signal extends by way of armature 242 and its resting contact, resting contact of 5 armature 267 and said armature, and relay 266 to battery. Relay 266, upon energizing, places ground on release trunk conductor 232 at armature 263, and at armature 261 places battery on the trunk line Z by 10 way of the following circuit: from battery through resistance R^e , resting contact of armature 246 and said armature, working contact of armature 261 and said armature, resting contact of armature 239 and said armature, 15 conductor 260 and the upper and lower right windings of repeating coil T^2 . The placing of battery on the trunk line Z operates the line relay of the repeater D^2 on the other end of the said trunk line as has 20 been hereinbefore described. The line relay of the said repeater energizes with the final result that the said repeater is made busy to the automatic switches in the No. 3 exchange, and the selector switch associated 25 with the said repeater is made ready for operation in the usual manner.

The operator now inserts the plug of the dial cord P' into the jack J^9 , whereupon relay 258 is operated over the following circuit: from ground by way of the ring contact of jack J^9 , the ring of the plug of the dial cord P' , calling device S' , tip of the 30 said plug, ring contact of the said jack, resting contact of armature 264 and said armature, resting contact of armature 240 and said armature, and the upper winding of 35 line relay 258 to battery. Line relay 258, upon energizing, closes a multiple point in the circuit from battery through resistance R^e to the trunk line Z. The operator now 40 operates the calling device S' in accordance with the first digit of the desired number. As soon as the calling device S' is moved from normal position, spring 145 makes contact with its working contact thereby closing 45 the following circuit: from ground by way of spring 145 and its working contact, the sleeve of the plug of dial cord P' , sleeve of jack J^9 , armature 265 and its resting contact, and relay 244 to battery. Relay 244 50 energizes and remains energized until the calling device S' is restored to normal position. Relay 244, upon energizing, opens at armature 246 a point in the original circuit 55 whereby battery was placed upon the trunk line Z thus leaving the said circuit closed only through armature 259 and its working contact. The calling device S' in returning to normal position interrupts the circuit of line relay 258 a number of times corresponding to the number for which the said device is operated. Relay 258 therefore at armature 60 259 sends a corresponding number of impulses to the line relay of the repeater D^2 and the said line relay repeats these im-

pulses to the associated selector which operates in the usual manner to raise its wipers to the desired level and rotate them to pick out an idle trunk line terminating in the said level. As a further result of the calling of the first digit, the busy visual associated with repeater D^2 is operated and the talking conductors are connected up in the same manner in which the same operations are performed by the repeater D as hereinbefore described. 70

The operator may now manipulate the calling device S' in accordance with the remaining digits of the desired number thereby completing the desired connection in the usual manner. When the called subscriber answers the operator tells him to remain on the line while she calls the subscriber in exchange No. 1. The operator now inserts the other plug of the cord circuit into the 80 jack J^7 thereby placing ground on release trunk conductor 256 by way of sleeve relay 110'. The conductors 255-257, inclusive, are understood to extend to and terminate in selector E^2 , Fig. 6, the banks of which are 85 multiplied with the banks of selector E' , Figs. 3 and 6. The results in this case are identical with those in the case in which the same plug was inserted into the jack J^6 and consequently need not be described. It will suffice to say the calling device S^2 is operated to complete the connection in the manner hereinbefore described. 90

When the subscriber in exchange No. 2 answers, the supervisory lamp L^5 is extinguished in the usual manner to give the operator answering supervision. The two subscribers may now converse with each other and when the conversation is finished they both hang up their receivers. When 100 the subscriber in exchange No. 2 replaces his receiver the supervisory lamp L^5 becomes lighted. The operator upon noting the lighted condition of lamp L^5 pulls down the connection. 105

When the plug is removed from jack J^7 the automatic switches in the No. 2 exchange are released in the usual manner. When the plug is removed from jack J^6 cut off relay 248 deenergizes and at armature 110 251 opens the circuit of the visual signal 247 and its multiples and the said signals accordingly deenergize. As a further result of the energization of the cut off relay 248 the circuit of relay 266 in the repeater D' 115 is broken. Relay 266 upon deenergizing, removes ground from release trunk conductor 232 at armature 263, and at armature 261 removes battery from the trunk line Z. When 120 battery is removed from the trunk line Z the connection in the No. 3 exchange is released in a manner hereinbefore described. 125

We shall now assume that the toll operator in exchange No. 3 receives a ticket calling for a connection between a subscriber 130

in exchange No. 3 and a subscriber in exchange No. 1. Upon the receipt of the said ticket, the operator in exchange No. 3 inserts a plug of an idle cord circuit into the 5 jack J^{10} thereby operating the associated cut off relay, which, upon energizing, closes a circuit for the associated visual signal and its multiples in front of the other operators. A branch of this circuit extends 10 into the repeater D, causing the said repeater to place ground on its associated release trunk conductor and to place battery on the trunk line Z so as to prepare the repeater D' in the No. 2 exchange, and its associated selector switch for operation in the 15 usual manner.

The operator now inserts the plug of a dial cord similar to dial cord P', Fig. 4, into the dial jack J^{11} and proceeds to call the 20 number in the usual manner. Upon referring to Fig. 6 it becomes apparent that in order to obtain connection with a trunk line such as trunk line X leading to the No. 1 exchange the toll operator in exchange No. 25 3 must dial the No. 01. The operator now operates her calling device in accordance with the digit 0 whereupon the selector E², Fig. 6, operates in the usual manner to raise its wipers to the tenth level and rotate them 30 in search of an idle trunk line extending to and terminating in a toll second selector, the selector F', for example. In response to the next digit 1 the selector F' raises its wipers to the first level and rotates them 35 to pick out an idle trunk line. We shall assume in the present case that the trunk line terminating in contacts 228-230, inclusive, is the first one found idle and consequently the one selected. That being the case the 40 connection is extended to the repeater D whereupon the usual circuits are closed with the result that the visual signal 106 is operated and battery is placed out on the trunk line X, the latter operation, however, having no utility in the present case. The operation of repeater D' under the same circumstances has been explained hereinbefore, consequently it is not necessary to explain the operation of the repeater D. It will 45 suffice to say that when the cut off relay 102 associated with the jack J^4 is energized, in the normal course of events, it opens at armature 103 the circuit of relay 100.

The operator in exchange No. 3 now operates her ringing key and thereby projects ringing current over the established connection to the repeater D and thence by way of trunk line X to relay 39 in exchange No. 1. Relay 39 upon energizing, closes the 50 circuit for line lamp L² in the usual manner thereby attracting the attention of the operator. The operator in exchange No. 1 now extends the connection to the desired subscriber by means of her cord circuit O.

55 When this connection has been completed

the toll operator in exchange No. 3 inserts the other plug of the cord circuit in use into the jack J^{12} and proceeds to call the subscriber in the No. 3 exchange in the usual manner. When the said subscriber answers 70 he may converse with the subscriber in the No. 1 exchange.

When the conversation is finished the two subscribers replace their receivers. When the receiver of the subscriber in the No. 1 75 exchange is replaced the usual supervisory signal is given to the operator in the said exchange. When the receiver of the subscriber in the No. 3 exchange is replaced the operator thereat receives the disconnect 80 signal and pulls down the connection but, just before doing so, she projects ringing current momentarily out over the connection to the exchange No. 1 thereby operating the relay 29 of the cord circuit O' and 85 lighting the lamp L' in the usual manner. The operator in exchange No. 1, upon noting the lighted condition of lamps L and L' pulls down the connection.

We shall now assume that the operator in 90 exchange No. 3 is required to complete a connection between a subscriber in the said exchange and a subscriber in exchange No. 2. The operator accordingly inserts a plug of an idle cord circuit into a jack, such as 95 the jack J^{10} , associated with an idle trunk line. When this is done the repeater D² is made busy to the automatic switches in the No. 3 exchange in the usual manner and battery is placed out on the trunk line Z 100 thereby making the repeater D' in exchange No. 2 and its associated selector switch ready for operation in the manner hereinbefore described. The operator in exchange No. 3 now operates her calling device in accordance with the number of the desired 105 subscriber whereupon a first and a second selector and a connector switch in the No. 2 exchange are operated to give access to the called subscriber's line.

The operator completes the connection to the subscriber in exchange No. 3, in a manner hereinbefore described, whereupon the two subscribers may converse with each other. When the conversation is finished 115 the two subscribers replace their receivers. The replacing of the receiver of the subscriber in exchange No. 3 brings in the usual disconnect signal. The operator, upon perceiving the disconnect signal, pulls down the 120 connection. When the plug is removed from the jack J^{10} the circuit conditions of the repeaters D² and D' are restored to normal and the connection to the subscriber in exchange No. 2 is accordingly released. 125 When the plug is removed from the jack J^{12} the connection to the subscriber in exchange No. 3 is released in the usual manner.

Referring now to Fig. 2, a point in con- 130

nection with the operation of the right end of cord circuit O' will be considered. It will be noticed that the repeaters D and D' are not arranged to give reverse battery supervision. Now, in case the operator in exchange No. 2 extends a connection to a subscriber in exchange No. 3, by way of the right hand end of cord circuit O' , jack J^6 , selector E', selector F', repeater D' and trunk line Z, unless special provision is made the supervisory lamp L^5 remains lighted during the entire time that the connection is established. In order to overcome this difficulty, the ground which is supplied to release trunk conductor 164, by the cord circuit O' , is led through the sleeve relay 110', the said relay being normally short circuited by ground placed on the said release trunk conductor by the release relay of a selector or connector switch. However, when a connection is extended to a repeater such as the repeater D' the relay 110' is not short circuited, because the repeater does not ground the release trunk, and, because it must supply ground to hold four relays energized, one in each repeater and one in each of the selectors, the said relay 110' accordingly energizes. Relay 110' upon energizing opens a point in the circuit of supervisory lamp L^5 , thereby extinguishing the said lamp.

In the connections hereinbefore described all excepting the two calls incoming to exchange No. 1 from exchanges Nos. 2 and 3, respectively, are completed automatically by the toll operator in the exchange in which the call originates without the aid of an intervening operator. If so desired, however, any of the connections hereinbefore described may be set up by the cooperation of two or more operators. This is obviously true in view of the fact that regardless of the repeaters such as D, D' and D² the toll lines are connected to their associated jacks at the operator's position in the same manner as they would be were the exchanges No. 2 and No. 3 manual instead of automatic. That is, while adding the automatic features to the inter-exchange toll trunks all the manual operating features have been retained. For example, if the toll operator in exchange No. 1 desires to extend a connection to some subscriber in exchange No. 2 she may insert the plug of an idle cord circuit into the jack such as the jack J^2 and operate her ringing key thereby projecting ringing current out on the trunk line X to cause the ringing response relay 100 associated with the jack J^4 to be operated to signal the operator in exchange No. 2. Relay 100 upon energizing, closes a locking circuit for itself and an energizing circuit for lamp L^3 . A branch of this circuit extends by way of the resting contact of armature 104 and the said armature to the visual signal 106 and its multiples. Therefore the said signals are energized. A branch of the energizing circuit for visual signal 106 extends by way of armature 123 and its resting contact, the resting contact of armature 166 and said armature, and relay 113 to battery. Upon energizing, relay 113 opens the circuit of line relay 116 at armature 129. Upon deenergizing, line relay 116 opens the control circuit of selector E' 75 whereupon the line and release relays of the said selector deenergize. When the operator in exchange No. 2 answers, the inserting of the plug into jack J^4 causes the ringing response relay 100 to be disconnected from in bridge of the conductors leading to the said jack, thereby extinguishing the associated lamp signal. The operator in exchange No. 1 now requests the operator in exchange No. 2 to complete the desired connection. The latter operator does this by inserting the other plug of the cord circuit in use into the jack J^6 after which she throws the proper key and operates her calling device in the usual manner to extend 80 the connection to the desired subscriber. Similarly the toll operator in exchange No. 2 may signal the operator in exchange No. 3 and request the latter to complete a connection to another subscriber in the said 85 exchange. The same is also true in case the toll operator in exchange No. 3 wishes the toll operator in exchange No. 2 to complete a connection to a local subscriber. Not only can the call intended for a subscriber in an 90 adjoining exchange be trunked through an intervening operator but also a call from the first exchange to the third exchange and vice versa can be completed with the aid of one or more intervening operators. For example a call from exchange No. 1 to a subscriber in exchange No. 3 may be handled as follows: The toll operator in exchange No. 1 may signal the operator in exchange No. 2 and request the latter to complete 100 the connection. The toll operator in exchange No. 2 has two courses to follow. She may either dial the complete connection from that point or she may extend the connection to an interexchange trunk line, such 105 as the trunk line Z, and signal the operator in exchange No. 3 and request the said operator to complete the connection. 110 It is well to explain at this point two alternate methods either of which may be 115 used by the operator in exchange No. 2 in extending a connection to a trunk line such as the trunk line X or Z, when completing calls that are to be trunked through the No. 2 exchange. Upon the receipt of such 120 a call, the operator may insert a plug in the jack such as the jack J^6 or J^7 , depending upon whether the call is coming from the No. 1 or the No. 3 exchange, and operate her calling device to obtain connection with 125

a trunk line to either exchange No. 3 or exchange No. 1.

- 5 The alternate method of handling such a call is to provide the operator in exchange No. 2 with an additional set of cord circuits, like the one shown in Fig. 7, which differs from the cord circuit O' in that the two ends are identical with each other and with the left hand or outgoing end of cord circuit O'.
 10 We shall term this group through switching cord circuits. In case an operator, who is supplied with both kinds of cord circuits, receives a call that is to be trunked to a third exchange she may, in case she so desires, remove the plug of the cord circuit used in answering the call, from the jack J⁴ or J⁸ depending upon from where the call is coming, and insert a plug of one of the through switching cord circuits in its place. The other plug of this through switching cord circuit is inserted into the proper jack. From this point the call may proceed automatically or manually as desired. This method of handling through calls is substantially the same as is employed in systems in which all toll calls are handled manually.

Having fully described and ascertained the features of this invention, what is considered to be new and desired to have protected by Letters Patent will be pointed out in the appended claims.

What I claim as my invention is:

1. In a telephone system, a repeater, an automatic switch having a line relay, a trunk line extending through said repeater and terminating in said switch, there being a normally open connection in each talking conductor of said trunk line at said repeater, means for transmitting an impulse of current over the trunk line, a line relay in the said repeater responsive thereto for transmitting an impulse to the line relay of said switch, and means in the repeater for closing said connections to establish a through talking circuit only after the switch has operated.

2. In a telephone system, a repeater, an automatic switch, a trunk line extending through said repeater and terminating in said switch, there being a normally open connection in each talking conductor of said trunk line at said repeater, means for transmitting a series of current impulses over the trunk line to said repeater, means in the repeater for repeating said series of impulses over said trunk to said switch, and contacts in said repeater operated responsive to the reception of one or more of the impulses of said series for closing said connections.

3. In a telephone system, a repeater, an automatic switch, a trunk line extending through said repeater and terminating in said switch, there being a normally open con-

nection in each talking conductor of said trunk line at said repeater whereby said trunk line is divided into incoming and outgoing sections at the repeater, means for transmitting a series of current impulses to said repeater over the talking conductors of the incoming section of said trunk line in parallel, means in said repeater for transmitting impulses to said switch over the talking conductors of the outgoing section of said trunk line in series, and a relay in said repeater operated responsive to the reception of one or more of the impulses of said series for closing said connections.

4. In a telephone system, a repeater, an automatic switch, a trunk line extending through said repeater and terminating in said switch, there being a normally open connection in each talking conductor of said trunk line at said repeater, whereby said trunk line is divided into incoming and outgoing sections at the repeater, a branch extending from the incoming section of the trunk line to a manual jack, a signalling device connected in bridge of the talking conductors of said branch, means for transmitting impulses over the incoming section of said trunk line to said repeater, the repeater being responsive thereto to transmit impulses over the outgoing section to said switch, relay contacts in said repeater operated responsive to the reception of one or more impulses for closing said connections, and other relay contacts also operated responsive to the reception of one or more impulses for disconnecting said signalling device from the bridge of said branch.

5. A combination automatic and manual toll trunking system comprising two exchanges and an interconnecting toll line, a repeater and an automatic switch individual thereto in the second exchange, the said toll line normally terminating in said repeater, means in the first exchange for generating impulses to operate said repeater and thereby operate said switch, there being means in the repeater for telephonically connecting the conductors of the toll line through to said switch, manual apparatus at the second exchange including plug and jack equipment optionally employed to establish a connection around said repeater from the toll line to said switch, and means in the second exchange associated with said manual apparatus for generating impulses to operate said switch.

6. In a telephone system, a trunk line extending through an automatic repeater and terminating in an automatic switch, a manual jack, a branch connecting said jack with the trunk line at a point between the said repeater and the said switch, means for controlling said switch by current impulses transmitted over the trunk line and relayed at said repeater, and means for controlling

said switch independent of the repeater by impulses transmitted over the said branch.

7. In a telephone system, a toll line connecting two exchanges, an automatic switch in the first exchange associated with and individual to said toll line, an operator's position in each exchange, branches of said toll line extending to jacks at said operators' positions, and means whereby either operator can control said switch to extend a connection.

8. In a telephone system, a toll line connecting two exchanges, an automatic switch in the first exchange associated with and individual to said toll line, an operator's position in each exchange, branches of said toll line extending to jacks at said operators' positions, means whereby either operator can establish a control circuit for said switch over the branch extending to her position, and calling devices at the operators' positions for interrupting the control circuits to direct the movement of said switch.

9. In a telephone system, a toll line connecting two exchanges, an automatic switch in the first exchange associated with and individual to said toll line, an operator's position in each exchange, branches of said toll line extending to jacks at said operators' positions, means whereby the operator at the first exchange can control said switch over two conductors of said toll line in series, and means whereby the operator at the second exchange can control said switch over two conductors of said toll line in parallel.

10. In a telephone system, a toll line connecting two exchanges, an automatic switch in the first exchange associated with and individual to said toll line, an operator's position in each exchange, branches of said toll line extending to jacks at said operators' positions, a normally disconnected toll line extension terminating in said switch, means whereby the operator in the first exchange can control said switch over the two sides of said extension in series, means whereby the operator in the second exchange can control said switch via the two sides of said toll line in parallel while the said extension is disconnected, and means for connecting the toll line with said extension.

11. In a telephone system, two exchanges, an operator's position in each exchange, a trunk line extending from a jack at the operator's position in the first exchange to an automatic switch in the second exchange, there being a repeater inserted in the trunk line at the second exchange ahead of said switch, a branch extending from the jack at the operator's position at the second exchange and connecting with said trunk line at a point between the said repeater and switch, a calling device at the operator's position in the first exchange for controlling said switch over the trunk line by means of

said repeater, and a calling device at the operator's position in the second exchange for controlling said switch over said branch independent of said repeater.

12. In a telephone system, two exchanges, an operator's position in each exchange, a trunk line extending from a jack at the operator's position in the first exchange to an automatic switch in the second exchange, there being a repeater inserted in the trunk line at the second exchange ahead of said switch, a branch extending from a jack at the operator's position at the second exchange and connecting with said trunk line at a point between the said repeater and switch, a calling device at the operator's position in the first exchange for controlling said switch over the trunk line by means of said repeater, a calling device at the operator's position in the second exchange for controlling said switch over said branch independent of said repeater, normally open connections in the talking conductors of said trunk line at said repeater, and means for closing said connections only when the trunk line is in use from the first exchange.

13. In a telephone system, a toll line connecting two exchanges and terminating in manual switchboards in both exchanges, an automatic switch associated with the toll line at the second exchange, a control circuit for said switch and means for closing it automatically when the toll line is taken for use at the first exchange, means whereby the operator at the first exchange can at her option transmit operating impulses over said toll line to control said switch or ringing current to signal the operator at the second exchange, and means responsive to ringing current for automatically opening the control circuit of said switch.

14. In a telephone system, a toll line connecting two exchanges and terminating in manual switchboards in both exchanges, an automatic switch associated with the toll line at the second exchange, a control circuit for said switch and means for closing it automatically when the toll line is taken for use at the first exchange, means whereby the operator at the first exchange can at her option transmit operating impulses over said toll line to control said switch or ringing current to signal the operator at the second exchange, a signalling device associated with the toll line at the switchboard in the second exchange and responsive to ringing current, means for disconnecting said signalling device in case the operator at the first exchange transmits operating impulses over said toll line, and means for opening said control circuit in case the said operator transmits ringing current over said toll line.

15. In a telephone system, a trunk line connecting two exchanges and having three

- branches at the second exchange, one branch extending through a repeater to an incoming switch, a second branch extending to a manual jack, and the third branch extending to multiply connected bank terminals in a plurality of outgoing switches, means for connecting with the trunk at the first exchange and for sending impulses thereto to operate said incoming switch by 5 means of said repeater, means for making the trunk line busy to said outgoing switches when it is first taken for use, and means operated responsive to the sending of impulses over the trunk line for making it busy at 10 the said manual jack.
16. In a telephone system, a two way trunk line connecting two exchanges, three branches of said trunk line at the first exchange, the first branch extending through 15 a repeater to an incoming switch, the second extending to a manual jack, and the third branch extending to multiply connected bank terminals in a plurality of outgoing switches, three similar branches at 20 the second exchange, means for operating one of said outgoing switches at the first exchange to connect with said trunk line via the third branch thereof, means for then transmitting current impulses over the trunk 25 line to operate the incoming switch at the second exchange by means of the associated repeater, means for at once making busy the second branch of said trunk line at the first exchange as soon as the trunk line is 30 connected with, and means for making busy the second branch at the second exchange also, the said last busying means being effective only after one or more impulses have 35 been transmitted over the trunk line.
17. In a telephone system, a two way trunk line connecting two exchanges, three branches of said trunk line at the first exchange, the first branch extending through a 40 repeater to an incoming switch, the second extending to a manual jack, and the third branch extending to multiply connected bank terminals in a plurality of outgoing switches, three similar branches at the second exchange, means for operating one of said outgoing switches at the first exchange to connect with said trunk line via the third branch thereof, means for then transmitting current impulses over the trunk line to operate the incoming switch at the second 45 exchange by means of the associated repeater, means for establishing busy conditions at the second branch in the first exchange and at the third branch in the second exchange before any impulses are transmitted over said 50 trunk line, and means for establishing a busy condition at the second branch in the second exchange, said last busying means being effective only after one or more impulses have 55 been transmitted.
18. A combination toll and local trunking system comprising a plurality of automatic exchanges interconnected by toll lines, local first selectors, second selectors, and connectors in each exchange for setting up local 60 connections, a toll repeater included in each toll line at each exchange, a toll first selector associated with each toll repeater, and multiple connections between the banks of the toll first selectors and the local first 65 selectors in each exchange, whereby the local second selectors in each exchange are made accessible to both toll and local first 70 selectors.
19. In a telephone system, lines, a link circuit, a supervisory signal associated therewith, means including a trunk line for extending a connection from said link circuit to a called one of said lines, means controlled by the response of the subscriber 75 on said called line for operating said signal, means including said trunk line for extending a connection from said link circuit to another called one of said lines, the last named connection being without means to operate said signal when the subscriber 80 on said other line answers, and discriminating means associated with said link circuit for operating said supervisory signal automatically when the last named connection is 85 set up.
20. In a telephone system, an operator's cord circuit, means including said cord circuit for setting up a connection to a called line by way of a local trunk line, means including 90 said cord circuit for setting up a connection to another called line by way of a toll line, a second local trunk line included in both 95 connections, a supervisory signal associated with said cord circuit, a circuit for said signal, means for controlling said signal over 100 said circuit responsive to the answering of the subscriber on the first named called line, and means for altering said circuit to control 105 said signal responsive to the extension of the last named connection to said toll line. 110
21. In a telephone system, a trunk line terminating in an automatic switch and having normally open contacts in the talking conductors, means responsive to a series of digit impulses received over the trunk line 115 for repeating such impulses past said open contacts to set said switch, and means for closing said open contacts responsive to the first impulse of said series.
22. In a telephone system, a trunk line 120 terminating in an automatic switch and having normally open contacts in the talking conductors, means responsive to a series of digit impulses received over the trunk line 125 for repeating such impulses past said open contacts to set said switch, a slow acting relay held energized responsive to said series of impulses, a second relay for closing said

open contacts upon energizing, and a circuit for energizing said second relay closed by said slow relay.

23. In a telephone system, a trunk line terminating in an automatic switch and having normally open contacts in the talking conductors, means responsive to a series of digit impulses received over the trunk line for repeating such impulses past said open contacts to set said switch, and means responsive to said impulses for closing said open contacts when the series starts and before the last impulse is received.

24. In a telephone system, a trunk line comprising two normally disconnected sections, a line relay energized over a portion of the first section when the trunk line is seized, a bridge across the second section closed by said line relay while the said two sections remain disconnected, said line relay responsive to a momentary interruption in its energizing circuit to momentarily open said bridge, and means controlled by said line relay responsive to said interruption for connecting said sections together.

25. In a telephone system, a trunk line incoming to an exchange and having two branches therein, one branch terminating in an automatic impulse repeater and the other terminating in a manual jack, a signal and a cut-off relay associated with said jack, and means in said repeater responsive to a series of impulses received over said trunk line for energizing said cut-off relay.

26. In a telephone system, a trunk line incoming to an exchange and having two branches therein, one branch terminating in an automatic impulse repeater and the other terminating in a manual jack, a signal and a cut-off relay associated with said jack, a line relay in said repeater energized when the trunk line is taken for use at the distant end and responsive to impulses received over said trunk line thereafter, and means controlled by said line relay while the same is operating responsive to such impulses for energizing said cut-off relay.

27. In a telephone system, a trunk line incoming to an exchange and having two branches therein, one branch terminating in an automatic impulse repeater and the other terminating in a manual jack, a signal and a cut-off relay associated with said jack, a line relay in said repeater, a circuit for said line relay closed at the distant end of said trunk line when the same is taken for use, and means controlled by said line relay responsive to an interruption of said circuit for energizing said cut-off relay.

28. In a telephone system, a trunk line extending to an automatic switch, a line relay for controlling the operation of said switch, a circuit for said line relay including a conductor of said trunk, means for connecting with said trunk line at the distant end and

for closing said circuit, means for then transmitting ringing current over said trunk, and means responsive to said ringing current for opening said circuit.

29. In a telephone system, a trunk line extending to an automatic switch, a line relay for controlling the operation of said switch, a circuit for said line relay including a conductor of said trunk, means for connecting with said trunk line at the distant end and for closing said circuit, means for then transmitting ringing current over said trunk, and means responsive to said ringing current for disconnecting said line relay from the trunk line.

30. In a telephone system a trunk line extending to an automatic switch, a line relay for controlling the operation of said switch, a circuit for said line relay including a conductor of said trunk, means for connecting with said trunk line at the distant end and for closing said circuit, means for then transmitting ringing current over said trunk, a ring-up relay responsive to said ringing current, and a relay controlled by said ring-up relay for opening said circuit.

31. In a telephone system, a trunk line extending to an automatic switch, a line relay for controlling the operation of said switch, a circuit for said line relay including a conductor of said trunk, means for connecting with said trunk line at the distant end and for closing said circuit, means for then transmitting ringing current over said trunk or for producing interruptions in said circuit to operate said switch, ringing current responsive means, a cut-off relay for disabling said responsive means, means associated with said switch for energizing said cut-off relay responsive to one of said interruptions, and means associated with said responsive means for opening the line relay circuit responsive to ringing current.

32. In a telephone system, a toll line connecting two exchanges and terminating in manual switchboards in both exchanges, an automatic switch associated with the toll line at the second exchange, a control circuit for said switch, means for inserting a source of current in said control circuit when the toll line is taken for use at the first exchange, means whereby the operator at the first exchange can at her option transmit operating impulses over said toll line to control said switch or ringing current to signal the operator at the second exchange, and means at the second exchange responsive to ringing current for inserting a second source of current in said control circuit in opposition to said first source to stop the flow of current thereover.

33. In a telephone system, a trunk line connecting two exchanges, a switch control circuit superimposed on said trunk line, a battery in each exchange normally excluded

- from said circuit, and means in one exchange responsive to ringing current transmitted over the toll line from the second exchange for inserting the battery at the first exchange in said circuit.
34. In a telephone system, a trunk line incoming to an exchange and terminating at a manual switchboard, a branch of said trunk line, automatic switches in said exchange having access to said branch, and means responsive to the seizure of said trunk line at the distant end for making the same busy to said switches while maintaining the same in idle condition at said switchboard.
- 10 35. In a telephone system, a trunk line incoming to an exchange and terminating at a manual switchboard, a branch of said trunk line, automatic switches in said exchange having access to said branch, means responsive to the seizure of said trunk line at the distant end for making the same busy to said switches without making the same busy at said switchboard, and means subsequently controlled over said trunk line for 20 making the same busy at said switchboard.
36. In a telephone system, a trunk line incoming to an exchange and terminating at a manual switchboard, a branch of said trunk line, automatic switches in said exchange having access to said branch, and separate means independently controlled over said trunk line after the same is seized for making the same busy to said switches and to the operator at said switchboard, 30 respectively.
37. In a telephone system, a trunk line, automatic switches having access to said trunk line, two jacks individual to said trunk line for use in connecting with said trunk line manually to extend connections thereover in opposite directions, and means responsive to the insertion of a plug in either jack for making said trunk line busy to said switches.
- 40 38. In a telephone system, a trunk line, automatic switches having access to said trunk line, two jacks individual to said trunk line for use in connecting with said trunk line manually to extend connections thereover in opposite directions, two relays associated with said two jacks, respectively, each relay being responsive when a plug is inserted in its associated jack, and a circuit closed by either of said relays for making said trunk line busy to said switches.
- 45 39. In a telephone system, a trunk line outgoing from a jack at a manual switchboard and extending to an automatic switch, a line relay for transmitting switch controlling impulses over said trunk line, a second jack at said switchboard, and a circuit for said relay terminating at said second jack.
- 50 40. In a telephone system, a trunk line outgoing from a jack at a manual switchboard and extending to an automatic switch, a line relay for transmitting switch controlling impulses over said trunk line, a second jack at said switchboard, a circuit for said relay terminating at said second jack, an operator's calling device, and a plug for connecting said calling device with said second jack.
- 55 41. In a telephone system, a trunk line comprising two inductively connected sections, a line relay controlled over the first section for repeating switch controlling impulses past said inductive connections, said line relay being normally disconnected from the first section, automatic switches having access to said trunk line, and means responsive to the seizure of the trunk line by one of said switches for connecting said line relay to the trunk line.
- 60 42. In a telephone system, a trunk line comprising two inductively connected sections, a line relay controlled over the first section for repeating switch controlling impulses past said inductive connections, said line relay being normally disconnected from the first section, automatic switches having access to said trunk line, a test conductor for said trunk line terminating in the banks of said switches, a relay energized over said conductor when the trunk line is seized by one of said switches, and contacts on said last mentioned relay for connecting said line relay to said trunk line.
- 65 43. In a telephone system, a trunk line comprising two inductively connected sections, a line relay for repeating switch controlling impulses past said inductive connections, a branch of said trunk line accessible to automatic switches, another branch accessible to an operator, an operator's switch control circuit normally terminating in said line relay, and means responsive to the seizure of said trunk line by one of said switches for disconnecting said line relay from said control circuit and for connecting it to said trunk line.
- 70 44. In a telephone system, trunk lines of two different classes, means including an operator's cord circuit and automatic switching mechanism for extending a connection to a trunk line of either class, supervisory equipment in said cord circuit, and means for automatically rendering said equipment operative or inoperative depending on the class of trunk line to which a connection is extended.
- 75 45. In a telephone system, trunk lines of two different classes, means including an operator's cord circuit and automatic switching mechanism for extending a connection to a trunk line of either class, a supervisory lamp in said cord circuit, and circuit arrangements for lighting said lamp only in case a connection is extended to a trunk line of a particular class.

46. In a telephone system, trunk lines of two different classes, means including an operator's cord circuit and automatic switching mechanism for extending a connection 5 to a trunk line of either class, a holding circuit for said switching mechanism including a sleeve relay in said cord circuit, a supervisory lamp in said cord circuit extinguished when said relay is energized, and 10 means associated only with the trunk lines of a particular class for closing said holding circuit over another path, whereby if a connection is extended to one of these trunk lines the said relay is shunted and the lamp 15 is lighted.
47. In a telephone system, a trunk line extending through an automatic repeater and terminating in an automatic switch, a manual switchboard, a branch connecting said 20 switchboard with the trunk line at a point between the said repeater and the said switch, means for controlling said switch by current impulses transmitted over the trunk line and relayed at said repeater, and means 25 for controlling said switch independent of the repeater by impulses transmitted over the said branch.
48. In a telephone system, a toll line connecting two exchanges, an automatic switch 30 in the first exchange associated with and individual to said toll line, an operator's position in each exchange, branches of said toll line extending to said operators' positions, and means whereby either operator can 35 control said switch to extend a connection.
49. In a telephone system, a toll line connecting two exchanges, an automatic switch in the first exchange associated with and individual to said toll line, an operator's position 40 in each exchange, branches of said toll line extending to said operators' position, means whereby either operator can establish a control circuit for said switch over the branch extending to her position, and calling devices at the operators' positions for 45 interrupting the control circuits to direct the movement of said switch.
50. In an automatic telephone exchange system, a group of toll lines incoming from another exchange, a toll switchboard where- 50 at said lines terminate, an equivalent group of outgoing toll service trunks terminating at said toll switchboard, each of said toll service trunks being individual to a particular toll line but normally disconnected 55 therefrom, and operator controlled automatic switches for extending said toll service trunks to local subscribers' lines to establish toll connections.
51. In an automatic telephone exchange 60 system, a toll line incoming from another exchange and extending through an automatic impulse repeater to an automatic switch, an operator's link circuit, and means for connecting the said toll line with said switch 65 for talking purposes either by way of said repeater or by way of said link circuit.
52. In an automatic telephone exchange system, a toll line incoming from another exchange and extending through an automatic impulse repeater to an automatic switch, a manual switchboard, a branch talking 70 circuit extending from said switchboard to a point between said repeater and said switch, another branch talking circuit extending from said switchboard to a point between said repeater and said toll line, and means for connecting the said toll line with said switch for talking purposes either by way of said repeater or by way of said 75 branch talking circuits in series.
- In witness whereof, I hereunto subscribe my name this 28th day of March, A.D., 1921.
- JOHN WICKS.
